HACK SAW

Carl-Arne Breger, Malmo, Sweden, assignor to
Sandvik Aktiebolag, Sandviken, Sweden

Filed Mar. 28, 1975, Ser. No. 562,924

Term of patent 14 years

Int. Cl. D8—03

U.S. Cl. D8—96

FIG. 1

FIG. 4

FIG. 2

FIG. 3

FIG. 1 is a perspective view of a hack saw;
 FIG. 2 is a side elevational view of the hack saw shown in FIG. 1;
 FIG. 3 is a top plan view; and
 FIG. 4 is an end view of the hack saw as seen from the handle end of the saw.

I claim:

The ornamental design for a hack saw, as shown and described.
